US0D1103521S

(12) **United States Design Patent** (10) **Patent No.:** **US D1,103,521 S**
(45) **Date of Patent:** **** Nov. 25, 2025**

(54) **MULTI-FUNCTION VACUUM CLEANER**

(71) Applicant: **NINGBO YELANG
PHOTOELECTRIC TECHNOLOGY
CO., LTD.**, Zhejiang (CN)

(72) Inventor: **Weisong Tu**, Zhejiang (CN)

(73) Assignee: **NINGBO YELANG
PHOTOELECTRIC TECHNOLOGY
CO., LTD.**, Zhejiang (CN)

(**) Term: **15 Years**

(21) Appl. No.: **29/950,294**

(22) Filed: **Jul. 2, 2024**

(30) **Foreign Application Priority Data**

Mar. 15, 2024 (CN) 202430133457.4

(51) **LOC (15) Cl.** **15-05**

(52) **U.S. Cl.**

USPC **D32/18**

(57) **CLAIM**

The ornamental design for a multi-function vacuum cleaner as shown and described.

DESCRIPTION

FIG. 1 is a first perspective view of a multi-function vacuum cleaner according to my new design;

FIG. 2 is a second perspective view thereof;

FIG. 3 is a front elevation view thereof;

FIG. 4 is a rear elevation view thereof;

FIG. 5 is a left side elevation view thereof;

FIG. 6 is a right side elevation view thereof;

FIG. 7 is a top plan view thereof;

FIG. 8 is a bottom plan view thereof; and,

FIG. 9 is a third perspective view thereof, incorporating with other tools.

The broken lines in FIGS. 1-9 illustrating certain portions of the multi-function vacuum cleaner form no part of the claimed design.

1 Claim, 9 Drawing Sheets
